UNITED STATES PATENT OFFICE

2,022,770

PYROTECHNIC DEVICE

William L. Kann, Pittsburgh, Pa.

Application April 6, 1933, Serial No. 664,813

9 Claims. (Cl. 102—25)

This invention relates to pyrotechnic devices, and more particularly to such articles known in the trade as salutes and toy torpedoes.

It is a general object of the present invention to provide novel and improved pyrotechnic devices of the type mentioned and novel methods of manufacturing the same.

More particularly it is an object of the invention to provide pyrotechnic devices in which the explosive compound is enclosed in a monolithic casing of hardened plastic material having the quality of breaking or shattering into fine particles as a result of the explosion whereby large flying parts are avoided.

Another object of the invention resides in the provision of a pyrotechnic device including a capsule enclosing the explosive compound and which is encased in an outer cover of plastic material formed thereabout while soft and permitted to harden.

A further object of the invention resides in the enclosing of a mass of explosive compound and detonating means within a monolithic plastic casing during the forming of the casing.

An important feature of the invention as applied to toy torpedoes resides in filling the capsule completely full of explosive material and some detonating agent such as gravel and then encasing it in a covering of plastic material and permitting the material to harden, and in so selecting this material that it shrinks materially on hardening to apply pressure on the walls of the capsule and compress the particles of gravel to render them immobile under ordinary handling of the device, thereby eliminating the danger of premature explosions during shipment by shifting of the gravel particles in respect to each other.

Another important feature of the invention resides in certain methods of assembling the pyrotechnic devices wherein the explosive is placed in a capsule which is then supported or suspended centrally in a mold and molten plastic material poured into the mold and the supporting or suspending means removed before the plastic material hardens, thereby permitting the encasing of the capsule in a monolithic or unitary cover which will resist the expanding gases resulting from the explosion substantially uniformly in all directions to produce the maximum report and to better insure against the flying of large portions or segments of the casing.

Other and further features and objects of the invention will be more apparent to those skilled in the art upon a consideration of the accom-

panying drawing and following specification, wherein are disclosed several exemplary embodiments of the invention, with the understanding, however, that various changes and modifications may be made therein such as fall within the scope of the appended claims without departing from the spirit thereof.

In said drawing:

Figure 1 is a vertical, central section through a mold showing a filled torpedo capsule in position therein;

Figure 2 is a similar view showing the plastic formed about the capsule and the supporting pins withdrawn;

Figure 3 is a similar view showing the torpedo after the casing has cooled and shrunk away from the walls of the mold and compressed the capsule and its contents;

Figure 4 is a central section through a modified form of torpedo;

Figure 5 is an elevation of a capsule and fuse for a salute, partly broken away to show the contents; and

Figure 6 is a section of the salute capsule showing the casing formed by dipping.

Toy torpedoes and salutes must be manufactured with both a view to safety to the user and manufacturer as well as a low cost. To insure safety to the user, it is essential that the covering or casing shall not remain in large pieces which might fly as a result of the explosion and inflict serious injury. To provide safety during manufacture and shipment, it is essential that the possibility of accidental explosion be reduced to a minimum, and to provide low cost it is necessary to eliminate insofar as possible manual operations and to reduce the total number of operations to a minimum. The torpedoes and salutes of the present invention, when constructed according to the exemplary methods to be described, meet all three of the requirements satisfactorily.

It will be understood that in the specification where the term "salute" is used, it refers to any explosive toy which is ignited by the use of a fuse and in which the main or primary purpose is to produce a loud noise. It will further be considered that a "toy torpedo" is that type of pyrotechnic device in which an explosive compound and suitable igniting means are enclosed in a casing in such a manner that an explosion takes place when the casing is violently impacted as by throwing it against a sidewalk, wall, or the like. The only difference in the two types of toys may be in the means for igniting the explosive, the

first requiring the application of fire and the second necessitating an impact or shock.

In the drawing, several methods and specific forms of torpedo and salute have been shown by way of example only. The torpedo of Figures 1, 2 and 3 consists essentially in four components, the outer casing 10, the capsule 11, the explosive compound 12, and the igniting means 13, which may be variously termed "impact devices", "ignition means", "impact igniting means", or more simply "gravel" since that is the common ingredient used for the purpose.

The gravel and explosive compound are enclosed in the capsule, which for convenience may comprise two telescoping parts as shown, and the whole is encased in the monolithic outer casing or cover, preferably of spherical configuration although any desired outer form may be selected.

In the manufacture of a torpedo, the explosive material is first selected. It may consist of any suitable explosive composition such as commonly used in torpedoes of this type. A satisfactory composition for the purpose includes at least two ingredients, one an oxidizing agent and the other a readily oxidizable substance. The first may be potassium chlorate and the second sulphur, but in most cases it is preferred to add to these two ingredients a third or sensitizing ingredient such, for instance, as antimony sulphide. The proportions of this ingredient control the sensitivity.

The impact igniting means may be any suitable hard granules, of an abrasive character if desired, but for the sake of convenience and cheapness, sized gravel is customarily used. It is preferred to have the size of the gravel such that but a few particles are in the capsule, for instance, not many more than six to ten.

The capsule 11 may be formed of any suitable tenacious material which is bendable or flexible and can be readily made and handled. A satisfactory form comprises a pair of telescoping paper or cardboard cups punched to the shape shown and one fitting over the other with sufficient closeness so that friction holds the parts together temporarily after they have been telescoped.

In the filling operation the smaller of the two cups is supplied with the requisite amount of gravel, and explosive compound either pre-mixed or with appropriate proportions of the separate ingredients which will later be mixed by a tumbling process or in the normal handling operation of the torpedoes. For the purpose of this invention, it is desirable that the gravel particles substantially fill the cup so that when the cap or cover is applied, there is none or only a very small empty space 15 remaining—the smaller this space, the better. The explosive need not completely fill the interstices between the particles of gravel.

The covering material to provide the casing for the capsule has two functions, first, to somewhat reinforce the capsule and hold the parts thereof together to provide a louder explosion, and second, to give a pleasing contour, size and appearance to the finished article. It is advantageous that this covering be substantially monolithic in order that there be no planes or areas of cleaving which will permit it to separate readily into several large particles which will fly. It is preferred to apply this casing by casting or molding it about the capsule, but it may also be applied by dipping the capsule into a molten mass in one or a series of successive operations to build up the requisite thickness. Then again, the ma-

terial in a semi-plastic state may be formed about the capsule, for instance, by rolling, pressing or other suitable operations. It is intended that the word "formed" used in the claims shall cover any manner of applying the casing to the capsule to produce a substantially seamless cover.

As suitable for the casing may be mentioned a number of materials, preferably waterproof or substantially so when hardened, and desirably not mixed with such a quantity of water as might wet the explosive composition during the covering process. For instance, the casing may well be made from rosin, stearic acid, paraffin, waxes of many forms and types, sulphur, pitch compositions, or any one or more of the above ingredients together with a filler such as an inert ground pigment or other colored pigments as iron oxide, lead oxide, chromium oxide, zinc oxide, or fillers which are inert and without substantial coloring characteristics, such as wood flour, ground paper, cellulose, or other suitable and cheap ingredients. Under certain conditions, mixtures as for instance, clay and glue, wood flour and silicate of soda, and the like, may be used. The main purpose is to obtain a composition for the casing which is substantially moisture-proof and which if heat softened is molten at a temperature not so high as to ignite the explosive composition when formed about the capsule, remembering that the cooling is rather rapid and the capsule offers some protection. The material should not be soft at any normally encountered atmospheric temperatures, nor should it be sticky. If not of the heat softened type, the plastic material should be quick-drying. Pleasing colors are desirable but not essential and can be obtained by some of the filling ingredients mentioned above.

The most important feature of the casing, however, is that it should contract or shrink very materially on hardening from its molten or plastic state for two purposes, first, in order to place the whole capsule under strong compressive stress which will cause it to engage the mass of explosive material and gravel and hold the same substantially under pressure at all times, thus preventing substantial relative movement of the gravel particles in respect to each other and insuring against ignition of the explosive compound except upon violent impact, which will displace the gravel particles due to momentum thereof and/or to deforming the casing; and second, in order that it may separate cleanly from the mold, if a mold is used.

In the molding operation, use is made of a lower mold 20 preferably having a semi-spherical upwardly extending cavity 21 and an upper mold portion 22 having a downwardly extending and correspondingly sized semi-spherical cavity 23. In order that the capsule and its charge may be held centrally of the spherical cavity of the combined mold parts, the lower portion of the mold is provided with three vertical holes 24 to accommodate the three slender metal pins 25 which at their lower or outer ends are secured to a carrying bar 26. The upper ends of the pins lie in a horizontal plane and are preferably arranged at the apices of an equilateral triangle less in extent than the bottom area of the capsule.

When the bar 26 is positioned as shown in Figure 1, the upper ends of these pins are properly positioned to receive the loaded capsule, after which the upper portion of the mold is put in position and secured and the molten plastic 75

material is poured in through the filling opening 30. During this operation entrapped air may escape through the openings 31. As soon as the plastic material has been poured in to fill the mold as shown in Figure 2, the pins 25 are withdrawn to the position illustrated in that view and the molten material allowed to close up the space recently occupied by the pins. In Figure 2 it will be seen that there is still a small space above the gravel and explosive and that the plastic material completely fills the mold.

In Figure 3 the mold is shown after cooling of the plastic, which takes place very rapidly because of the chilling effect of the metal walls of the mold, so that actually the torpedoes can be removed very shortly after the pouring operation. The shrinking effect of the plastic material causes it to draw away from the mold as shown at 32, leaving a bright, clean, shiny surface on the torpedo and entirely freeing it from the mold so that it can be readily picked out when the upper half of the mold is removed. Any sprue remaining, as at 33, may be broken or cut off as desired. The effect of the shrinkage of the material on the capsule may be noted in Figure 3, for it is shown as reduced in size and at all points in engagement with the material filling the same so that the gravel is held rigid under compression and relative movement of the particles thereof is prevented.

In Figure 4 is shown an embodiment of a torpedo which differs in some respects from that shown in Figures 1, 2 and 3 but which functions in the same manner. It contains the same capsule and charge, but as a first covering for the capsule there is a layer 35 of extremely tenacious material preferably placed on the capsule by a dipping operation. It may comprise a plastic having fibers incorporated therein or it may be some very tenacious plastic, as for instance, rosin, combined with a plasticizer. If this material remains sticky for any appreciable period after dipping, the coated capsules can be thrown on a revolving or shaking table covered with some powdered material to prevent sticking of the capsules together. This extremely tenacious coating reinforces the capsule sufficiently to provide a complete torpedo insofar as explosive qualities are concerned, but for the purpose of giving it a suitable configuration and appearance and a sufficiently large size to be attractive to the purchaser, the outer covering or casing 36 is provided. It will be appreciated that it can be formed in the manner described in connection with Figures 1, 2 and 3, or in any other suitable manner, as by pressing, forming, rolling, or otherwise arranging the plastic casing thereabout. The physical characteristics of this outer casing 36 need not be so carefully selected as those where the casing is the only one about the capsule. Being used substantially for body only, the cover 36 can be largely a light-weight filling material held together insecurely only by a suitable binder. It is advantageous to have this material fairly frangible so that the very complete explosion resulting from the rupture of the tenacious casing will cause the outer covering to be broken into minute fragments so that none of them will fly and be potential sources of danger.

Since the inner coating can well be made waterproof, this outer casing 36 can be a simple mixture of glue and a filler such as powdered clay, sawdust, wood flour, cellulose, paper pulp, or the like. Under these conditions it will readily retain a coloring material either incorporated

therein or applied by spraying, dipping, brushing, or the like.

In forming a salute, the operation is quite similar to forming a torpedo except that the gravel is left out and a fuse 40 inserted through one wall 5 of the capsule, as shown in Figure 5, preferably prior to filling and assembling the capsule parts. This fuse may stick out through the opening used for filling the mold and may be relied on to suspend the capsule centrally in the mold instead of 10 using the supporting pins 25.

Instead of having the fuse extend out through the filling opening where it might be in the way, particularly where machine filling is relied on, there can be provided at the junction of the two 15 molded parts grooves which combine to form a tubular passage for the fuse so that it can extend horizontally out from the top of the mold shown in Figure 1. The rigidity of the fuse is adequate even under these conditions to support the capsule substantially centrally of the chamber in the mold while the mold is receiving its charge of plastic material through the opening 30 as in the case of the torpedo. This construction permits the removal of the sprue more readily without 25 danger of damaging the fuse and insures a tighter engagement of the plastic material with the fuse for obvious reasons.

In the case of salutes, if it is desired to dip them, for instance, instead of molding the casing, 30 the fuse makes a suitable handle for the purpose, and satisfactory salutes, as shown in Figure 6, have been made by dipping once or a number of times into melted stearic acid colored if desired to give a pleasing appearance. If dipping is to be 35 resorted to for torpedoes, they may be carried in baskets or otherwise suitably held during the operation.

Having thus described the invention, what is claimed as new and desired to be secured by 40 Letters Patent is:

1. In a toy torpedo, in combination, a capsule of readily deformable material, explosive mixture and impact igniting means therein and means maintaining said capsule under such compression 45 as to prevent shifting of the impact igniting means therein.

2. In a toy torpedo, in combination, a charge of explosive, impact igniting means mingled with said explosive and an enclosing capsule holding 50 the conglomerate under sufficient pressure to prevent relative shifting of the igniting means under normal handling conditions.

3. In a toy torpedo, in combination, a charge of explosive, impact igniting means commingled 55 therewith, an enclosing capsule closely surrounding the conglomerate and a plastic casing completely enclosing said capsule and holding it under compression sufficient to prevent relative shifting of the igniting means under normal handling 60 conditions.

4. In a toy torpedo, in combination, a charge of explosive, impact igniting means commingled therewith, an enclosing capsule closely surrounding the conglomerate and a casing formed completely around said capsule, said casing being of a plastic material which shrinks sufficiently on hardening to hold the conglomerate immobile. 65

5. A toy torpedo comprising, in combination, a mixture of gravel and an explosive composition, a 70 completely enclosing capsule therefor closely fitting the mass, a casing of a hardened plastic which will break into fine particles on explosion, said plastic having the property of shrinking on hardening so that when applied to the capsule 75

when soft it will contract the capsule to hold the mixture relatively immobile therein.

6. A toy torpedo comprising in combination, a capsule of yielding material, explosive composition and gravel filling said capsule and a casing of hardened plastic material compressing said capsule to immobilize the gravel therein.

7. A toy torpedo comprising in combination, a capsule, explosive composition and gravel filling said capsule and means holding the gravel under compression to immobilize the same.

8. A toy torpedo of the type adapted to be ex-

ploded on impact comprising in combination, a mass of explosive and gravel and a completely enclosing unitary casing formed and shrunk tightly thereabout.

9. A toy torpedo of the type adapted to be exploded on impact comprising in combination, a mass of explosive and gravel, a covering of tenacious material enclosing said explosive and gravel and contracting the same and a frangible casing over the covering to increase the size of the **10** torpedo.
